UNITED STATES PATENT OFFICE.

ALBERT FIELDS, OF RED OAK, IOWA.

ATTACHMENT FOR PRINTING-PRESSES.

No. 918,428.

Specification of Letters Patent. Patented April 13, 1909.

Application filed December 9, 1908. Serial No. 466,659.

To all whom it may concern:

Be it known that I, ALBERT FIELDS, a citizen of the United States of America, residing at Red Oak, in the county of Montgomery and State of Iowa, have invented new and useful Improvements in Attachments for Printing-PresSES, of which the following is a specification.

This invention relates to attachments for printing presses, and one of the principal objects of the same is to provide simple and efficient means for preventing the feed of ink from the fountain to the distributing rolls when the impression of the press has been thrown off.

In many of the job printing presses, as at present constructed, means are provided for throwing off the impression when a sheet is improperly fed to the guide pins or when for any purpose the press feeder desires to leave the press temporarily. Under these conditions the ink fountain is under constant operation and continuously feeds ink to the distributing rollers when the impression is thrown off. When the feeder returns to the press and starts to again feed the job, the ink fed by the fountain and carried by the form rollers over the form is largely in excess of the amount required. As a result of this condition some of the ink must be removed from the distributing rollers. It is to overcome this defect in feeding ink from the fountain that my invention is designed.

The objects and advantages above referred to may be attained by means of the construction illustrated in the accompanying drawing, in which,—

Figure 1 is a side view of a portion of a printing press of well known construction having my attachment connected thereto in position for operation. Fig. 2 is a plan view of my attachment disconnected from the press.

Referring to the drawing, the numeral 1 designates the frame of a job printing press of well known construction; 2 is the cam; 3 is the arm; 4 is the platen, and 5 is the throw-off lever.

6 is the ratchet wheel on the end of the fountain roller; 7 is the roller which takes the ink from the fountain roller and deposits it upon the distributing drum 8, the roller 7 being intermittently moved against the fountain roller by means of the cam roller 9 actuated by the cam 2, said roller being con-

nected to a lever 10 pivoted at 11 to the frame of the machine. The distributing rollers are mounted in the frame 12, while the form rollers are mounted in the frame 13.

In presses of this character means are provided for carrying the form rollers up and holding them above the platen so that as the press is operated after the impression has been thrown off the platen will not come in contact with the rollers.

The ratchet wheel 6 on the end of the fountain roller is actuated intermittently by means of a spring pawl 14 pivoted upon the end of a lever 15, said lever being pivoted at 16 to the frame and provided with a weight 17 at its outer end. A cam roller 18 is journaled in the weight 17, said roller bearing upon the cam wheel 2. The track for the roller 18 is provided with a depression 19, shown in dotted lines in Fig. 1. When the roller 18 drops into the depression 19, the pawl 14 slips over one tooth of the ratchet wheel 6, and as the roller 18 passes over the elevated portion of the track on the cam wheel 2, the pawl 14 pushes the ratchet wheel 6 forward, thus bringing a quantity of ink upon the face of its roller in position to be conveyed by the roller 7 to the distributing drum 8.

My invention is designed to prevent the roller 18 from following the depression 19 in the track upon the cam wheel 2 and hence to prevent the movement of the ratchet wheel 6 and the feeding of the ink from the fountain during the time that the impression is thrown off the press.

In carrying out my invention I utilize a spiral spring *a* having a hook *b* at one end, said hook being connected to an eye *c* attached to the weight 17 of the lever 15. The spring *a* passes over a grooved roller *d* mounted in a bracket *e* provided with a bolt hole *f* by means of which said bracket may be secured to the frame 1 of the press. The end of the spring *a* opposite the hook *b* is connected to a plate *g* provided with a hole *h*, by means of which said plate is connected to the throw-off lever 5 of the press.

The operation of my invention may be briefly described as follows: When the impression is thrown off, the lever 5 assumes the dotted line position in Fig. 1, and this pulls upon the spring *a* to lift the weight 17 and to prevent the wheel 18 from riding in the depression 19 of the cam wheel 2. Thus

the pawl 14 fails to actuate the ratchet wheel 6, and as a result ink is not fed from the fountain roller to the distributing rollers, and hence the ink is kept uniform so that when the feeder returns to the press the ink is of the same density as when he left it.

My invention is of simple construction, can be readily applied to any form of job press with but slight alteration; the cost of production is slight, and the device operates smoothly and efficiently for its purpose.

I claim:

1. An attachment for job printing presses comprising a spring connected at one end to the lever which operates the fountain roller, a bracket secured to the press frame, and a roller mounted in said bracket, said spring extending over said roller and the

opposite end of said spring being connected to the impression throw-off lever.

2. The combination of an ink fountain for a job printing press, a ductor roller, a pawl for actuating said ratchet wheel, a lever upon which said pawl is mounted, a cam roller on said lever, a cam for actuating said lever, a spring connected to said lever at one end and connected at its opposite end to the impression throw-off lever, and a bracket having a roller mounted thereon for guiding said spring.

In testimony whereof I affix my signature in presence of two witnesses.

ALBERT FIELDS.
